RIVET SPINNING MACHINE

Philip X. Noel, Bridgeport, Conn., assignor to
The Grant Manufacturing and Machine Co.,
Bridgeport, Conn., a corporation of Connecticut

Application September 23, 1931
Serial No. 564,600

5 Claims. (Cl. 78—53)

This invention relates to new and useful improvements in rivet spinning machines and more especially the spinner type of riveters adapted for heading relatively small rivets when applied to 5 and as used in the assembling of structural parts.

An object of the invention is to provide a light form of rivet spinning machine of this general type that is especially adapted for close work, such as spinning heads on rivets located between 10 parts of assembled structures, and where it is necessary to position the spinning head within the structure being assembled. The machine is especially adapted for spinning heads upon rivets used in fastening together parts of children's toys, 15 such as sleds and the like, wherein the brace members are riveted to the wood parts and metal runners.

A further object of the invention is to provide in this type of machine various fine adjustments 20 not only of the supporting table, but to limit the movement of the spinning head to and from the work so as to better adapt the machine to be used by inexperienced operators.

The machine further includes a novel means 25 of supporting and assembling the operative parts of the machine whereby the same is hingedly mounted so that the spinning head may be advanced to and returned from the work and whereby the power applied for rotating the spinning 30 head is directly over the hinged axis of the supporting arm and including a driving shaft that is at a right angle to said axis.

Further features of the invention reside in the spinning head, its rollers and means for lubricating the same, as will be later more fully described. 35

With these and other objects in view, the invention resides and consists in the construction and novel combination and arrangement of parts hereinafter more fully described, illustrated in 40 the accompanying drawing, and pointed out in the claims hereto appended, it being understood that various changes in the form, proportion, size, and minor details of construction within the scope of the claims may be resorted to without 45 departure from the spirit, or sacrificing any of the advantages of the invention.

Similar characters of reference denote like or corresponding parts throughout the several figures of the accompanying drawing forming a 50 part of this specification and upon which

Fig. 1 shows a vertical sectional elevational view of my improved type of rivet spinner;

Fig. 2 shows an enlarged detailed vertical cross 55 sectional view of the spinning head, its driving

gear, and portion of the supporting arm in which it is journaled;

Fig. 3 is a further enlarged and similar vertical cross sectional view through the lower end portion of the spinning head, including its rollers, 60 better to illustrate the means for oiling the roller bearings; and

Fig. 4 shows a somewhat similar vertical cross sectional view of a slightly modified form of spinning head.

Referring in detail to the characters of reference marked upon the drawing, 10 represents a pedestal adapted to be supported on a floor and to carry all the parts of the machine. This pedestal is preferably hollow having a longitudinal vertical front opening 11 and a somewhat similar longitudinal opening 12 in the rear side. Its top or bed end 13 is closed and relatively heavy, better to support the swinging arm 14 again to be referred to.

The parallel edges of the front opening 11 are finished to form vertical ways 11^a to receive corresponding vertical ways of the work table 15 that is adapted to be adjusted vertically on the pedestal and secured in said adjustment by means of a 80 clamping screw 16 that engages a nut 17 positioned within the pedestal and against the inside of the two vertical edges of the opening.

A convenient means of adjusting this table upon the pedestal is provided upon the front side 85 immediately beneath the table and is adapted to be operated when the clamping screw 16 is slightly loosened. This adjusting means comprises a yoke 18 that is fitted against the face of the two vertical ways of the pedestal and is 90 provided with a central hole to accommodate a clamping screw 19 that extends therethrough and engages a nut 20, similar to the nut 17 before mentioned, and which like the last mentioned nut engages the inner vertical edge portions of the pedestal adjacent the front opening. An adjusting screw 21 is seated in the yoke 18 and is provided with a lock nut 22. The head of this adjusting screw is seated against the under edge portion of the table so that with turning of the screw in one direction the table can be raised, when the screw 16 is loosened, whereas with the turning of the screw in the opposite direction the weight of the table will descend as by gravity, and when adjusted to the desired 105 position is secured by the clamping of the lock nut and the tightening of the screw 16.

The horizontal surface portion of the table is provided with a hole 23 to receive a mandrel 24 which may vary in form according to the 110

particular type of work to be supported thereon. This mandrel includes a larger head portion adapted to be seated on the table and a cylindrical shank portion of a smaller diameter 5 adapted to fit in the hole 23 of the table. This shank portion is provided with a central longitudinal tapped hole to receive a clamping screw 25 that is positioned therein from the underside after first having passed through a washer 26 10 that engages the underface of the table, and whereby upon the turning of the screw the mandrel is tightly clamped to the table in position to support the work for operations thereon.

To the top or table end of the pedestal, I secure by means of bolts 27 a pair of aligned bearings 28-28. These bearings serve to support the trunnions 29 of the swinging arm 14, forming a pivotal support, whereby the arm is adapted to be swung for the purpose of raising and 20 lowering its spinning head with relation to the work upon which it is to operate. This swinging arm is of a special construction and includes a depending curved end portion 30 that pivotally connects through the rear opening of the pedestal 25 with the longer one 31 of two toggle members, the other member 32 of said toggle being hingedly connected to a fixed pin 33 that is secured in the opposite side portion of the pedestal. A pin 34 connects the two toggle members with a 30 shackle 35 carried on the upper end of the vertical connecting rod 36. The first mentioned toggle member 31 includes an extended end portion 37 which is positioned and proportioned so as to engage a sleeve 38 upon the pivotal pin 33 when the mechanism is operated through the connecting rod 36 to draw down the pivotally connected ends of the two toggle members in a way to lift the curved end 30 of the arm and lower its head portion, and thus limit the downward movement of said head. The amount of 40 this movement may be readily adjusted by the turning of the link 36 with relation to the shackles and the clamping of the nuts 39 thereon.

An adjustable stop 40 including a lock nut 41 45 is positioned in the top of the pedestal in alignment with a boss 42 on the underside of the arm, which is adapted to strike the head of the screw and arrest the downward movement of the curved end of the arm 14 and the upward movement of the head end. The arm is adapted to be swung on its pivot through a foot lever 43 hingedly supported upon a pin 44 secured to opposite sides of the pedestal, said lever being operable against the action of a spring 45, one 50 end of which is attached to the foot lever as at 46, and the other to a pin 47 secured to the pedestal. A shackle 48 attached to the lever 36 is pivotally connected to the foot lever so that with the operation of the foot lever by the spring 60 or against the action thereof, the link will impart movement to the toggle which in turn rocks the swinging lever with relation to the pedestal and its table.

The driving shaft 49 for the spinning head 50 65 is positioned above the axis upon which the arm is hinged to swing and at a right angle with respect to said axis. This shaft is journaled in aligned bearings 51 of the swinging arm and is provided with a belt pulley 52 positioned immediately above the axis of the trunnions so that the pull of an attached belt, when connected to an overhead driving pulley, will be upward and in alignment with the axis of the trunnion so as to not materially interfere with the swinging 70 operation of said hinged arm. Upon the forward

end of this driving shaft is mounted a bevelled gear 53 that meshes with and drives a somewhat similar bevelled gear 54 secured to the spindle 55 of the spinning head.

The spindle 55 is mounted vertically in the short or head end of the swinging arm and at a right angle to the before mentioned driving shaft, and as shown in the drawing the bevelled gears employed to drive the spindle from the driving shaft may be enclosed with a suitable sheet metal covering 56, as shown in Fig. 1. The spindle is mounted in a babbitt bearing 57 of the arm and is provided with an annular roller thrust bearing 58 positioned between the underside of the arm and an annular shoulder 59 of the head. 80

The head includes a pair of rollers 60 having suitable annular surfaces to insure the formation of the desired form of rivet head. These rollers are positioned in separate slots or pockets 61 that are formed longitudinally of and at an acute angle to the axis of the head so that the inner edges 62 of the exposed portion of the rollers will engage and run together at the underside of the head to form a combined closed operating surface, whereas the inner or upper edges 90 will be positioned in spaced relation to each other. These rollers are mounted to turn on a bearing 63 which may be a pin or screw, as shown in the drawing, with a head upon one end, positioned in a pocket 64 of the head 50 and a 100 threaded end to engage the tapped hole 65 of the spinning head. A tapered hole 66 is provided in each roller to receive the pivotal screw so that the inner lower wall of this hole will at all times bear flush with the underside of the bearing 110 screw, thus allowing a firm engagement of the screw with the rollers in a way to insure a firm operative support of the rollers within the head.

Means for oiling the head and more especially the rollers is also provided and includes a central 115 reservoir 67 which has one or more intersecting radial holes 68 that communicate with an annular pocket 69 which in turn is supplied with a suitable lubricant through the intake hole 70 formed in the head end of the arm, and having a 120 lubricant intake 71. A small passage extends down from the reservoir between the upper portion of the rollers so as to feed the lubricant thereto. This passage 72 may be in the form of a small inserted pipe, as shown in Figs. 2 and 4, 125 or may be formed in the web of the head which extends between the two rollers, as shown in Fig. 3. It is important that this lubricant passage extend clear through to the bearing as otherwise the oil will be thrown out of the pockets on to 130 the work by centrifugal force.

In the modification shown in Fig. 4, the head 50^a is threadably attached to the spindle 52^a and also includes a reservoir to which lubricant is supplied through the intake 71 so that the lubricant may be fed down through the passage 72 to the bearings, as in the other form. 135

In Fig. 1 I have shown, in dotted lines, a part of a sled wherein "a" and "b" represent wood portions of the sled frame, "c" an iron bracket, 140 and "d" an iron runner. This is a class of work which the machine is especially adapted to do, as will be seen, the work being positioned under the runner "d" to operate upon the head end of the rivet "e" whereby the bracket "c" is secured to the wood frame members "a" and "b". It has not been practical heretofore to do this class of close work upon any commercial form of machines for the reason that the spindles of all such machines were longer, and the general 145 150

design of the machine so different that it was not possible to get the riveting head of these machines in between the fixed distances of the assembled work in a way to spin the head on the rivet.

Having thus described my invention, what I claim and desire to secure by Letters Patent is:

1. In a machine of the class described, a spinning head including a fixed bearing, spaced apart rollers mounted on the bearing, the said head being provided with an oil reservoir above the roller, and a central lubricant passage extending from the said reservoir down between the rollers to the bearing.
2. In a machine of the class described, a spinning head including a pair of rollers disposed longitudinally of and at acute angles with relation to the axis of the head, and provided with an oil reservoir, an oil passage connected with the reservoir, a pipe extending from the said passage down between the rollers to the bearing.
3. In a rivet spinning machine, the combination with a pedestal, of a curved arm hingedly mounted thereon, a driving shaft journaled in said arm above and at a right angle to its pivotal axis, a spindle mounted in the arm at a right angle to said driving shaft, gears connecting the driving shaft and spindle for operating the latter, the said spindle including a spinning head having a roller adapted to form a rivet head, and

foot power means and toggle connection with the swinging lever to move the spinning head to and from operative positions.

4. In a machine of the class described, an arm, a spinning head including a spindle mounted in the arm, means for operating the spindle and head, the said spindle having a peripheral annular groove, a reservoir and oil passages extending from the groove to the reservoir, a bearing secured in the spinning head, spaced-apart rollers mounted on the bearing, a central lubricant passage extending from the reservoir down between the and apart from the rollers to the bearing.

5. A rivet spinning machine comprising a pedestal, a work table mounted on the pedestal, a curved arm hingedly mounted in the pedestal and having a depending end portion, a toggle connecting said end portion and pedestal, a lever and link connection for operating the toggle, means for limiting the movement of the toggle and arm in one direction, a driving shaft journaled in the arm above and at a right angle to its pivotal axis, a spindle journaled in said arm and carrying a spinning head, gears connecting the driving shaft and spindle for operating the latter, a pulley mounted on the driving shaft immediately above the pivotal axis of the lever so that the pull of the driving belt will be in direct alignment with the said axis.
